UNITED STATES PATENT OFFICE

2,528,825

CONVERTIBLE BATHTUB APPLIANCE

Rebecca Graves, Spokane, Wash.

Application November 12, 1946, Serial No. 709,258

2 Claims. (Cl. 248—168)

1

My present invention relates to an improved convertible bath tub appliance of the general type used in bathing babies and having a cradle portion in which the baby may be immersed with the head above the water line in the conventional bath tub, and a stretcher which may be extended on the frame to provide a support for the baby after the bath and during the drying and powdering operations.

The invention also includes novel and unique arrangements for supporting the various structures and means permitting the folding of the legs of the appliance for ease of storing.

In the accompanying drawings I have illustrated one complete example of the physical embodiment of my invention according to the best mode I have thus far devised, but it will be understood that various changes and alterations may be made in the exemplified structure within the scope of the appended claims.

In the drawings:

Fig. 1 is a plan view showing the invention with the cradle portion in suspended position and having the table portion secured at one end out of the way.

Fig. 2 is a perspective of the frame locked in a standing position shown without a cradle and table top and having a tray supported at the end thereof.

Fig. 3 is a section taken through a tub showing the stretcher in cross section and showing the device hanging from a towel rack when not in use.

Fig. 4 is a perspective of the locking member.

Fig. 5 is a detailed sectional view of one end taken on line 5—5 of Fig. 1.

In carrying out my invention I employ a rectangular frame of suitable material and including parallel side bars 2 and 4, and the ends of these bars are secured in transversely arranged bores in a pair of end bars or cross bars 6 and 8. On the under side of each of the end bars at 10, a complementary bar 12 is hinged, and a pair of legs 14, having pads or feet 16 for engagement with the bottom of the tub T, is fastened to and depends from the hinge bar, so that the two pairs of legs may be folded into dotted line position of Fig. 5, for storage purposes. It will be seen that the hinges 10 are attached to the under faces of the fixed bars, and to the inner sides of the hinged bars along their lower portions, so that the upper horizontal portions of the hinge bars contact the lower horizontal portion of the fixed bars when the frame is supported on the four legs.

2

This relationship between the pairs of fixed bars and the pairs of hinged bars braces the frame, and provides an exterior angular groove at each end of the frame in which a base block 5 is located and attached on the outer face of each of the fixed end bars 6 and 8, and a vertically slideable snap fastener, of spring metal, as 20 is mounted on each brace block for retaining a hinge bar in upright position.

10 The rectangular fasteners 20 are each provided with an upper handle-flange 22, and a horizontal rib 24 for enhancing the resiliency of the fastener, and two spaced vertical slots 26 in the upper portion of the fastener coat with headed pins, screws, or nails 28 secured in the base block. In the position of Fig. 5 the fasteners 20 coat with the fixed end bars to retain the hinged bars and legs in upright position, and the fasteners may be lifted from contact with the hinge bars to allow folding of the legs. Thus, the legs may be folded into parallelism with the side bars and the appliance may then be suspended from a suitable support as a towel rack 30 with the frame indicated by dotted lines in Fig. 3.

In Figs. 1 and 3, a cradle 32 of suitable flexible material is equipped with tabs or straps 34 having rings 36 slidably mounted on the side bars 2 and 4, and the cradle is preferably suspended in position so that the head end will be higher than its foot end. When desired the flexible cradle may be collapsed and folded by sliding the rings 36 to one end of the frame, and a flexible stretcher 38 may be substituted for use.

30 The stretcher is equipped with tabs or straps 40, and slide rings 42 on the side bars, and for compacting the stretcher when out of use, one end of the stretcher is equipped with a strap 44 and attaching loop 46 for detachably fastening the folded stretcher on a pin 50 fixed to end bar 6, which performs a function similar to the pin 48 on bar 8 to which the cradle may be attached in collapsed and folded position.

45 For convenience in the process of bathing a detachable soap tray 52 having depending and supporting legs 54 is provided, and the lower ends of these legs or pins are detachably inserted in complementary sockets or holes in the end bar 8.

Having thus fully described my invention what I claim as new and desire to secure by Letters Patent is:

55 1. In the bath tub appliance described, the combination with a rectangular frame including

a pair of fixed end bars, and an exterior horizontal base block mounted along the upper portion of each end bar, of a pair of foldable bars each having a pair of fixed legs, hinges uniting the lower edges of the fixed bars with the lower inner side portions of the foldable bars, and detachable fastening means coacting with the outer sides of the blocks and the foldable bars for retaining the latter bars in fixed position.

2. In the bath tub appliance described, the combination with a fixed end bar and a foldable hinged bar forming an upper exterior groove, and a pair of legs depending from the hinged bars, of a base block mounted in the groove on the outer side of the fixed bar, spaced retaining 10 and head pins mounted on the base block, and

5 a slotted and vertically slidable spring fastener mounted on the pins in frictional engagement with the outer side of the hinged bar.
